UNITED STATES PATENT OFFICE.

PERCY W. WHITE, OF CLEVELAND HEIGHTS, OHIO.

HEADLIGHT.

Application filed October 10, 1921. Serial No. 506,657.

To all whom it may concern:

Be it known that I, PERCY W. WHITE, a citizen of the United States, residing at Cleveland Heights, in the county of Cuyahoga and State of Ohio, have invented a new and useful Headlight, of which the following is a specification.

This invention relates to improvements in headlights more especially designed for use 10 on motor-vehicles.

One object of this invention is to produce an improved and highly practical headlight having such construction that effective illumination of the roadway in front of the 15 motor-vehicle is attainable without objectionable projection of light-rays at a height requiring dimming of the light-transmitting panel which participates in the formation of the front of the headlight and through 20 which occurs the transmission of light for illuminating the roadway, and that the projection of a beam of light into the eyes of the driver of an approaching vehicle, and waste of illuminating power, are success- 25 fully prevented.

Another object is to provide improved means for adjusting a mirror which forms a part of my improved headlight and is employed in reflecting rays of light over and 30 onto the roadway.

Another object is to provide improved means for the attachment, to the headlight casing, of a flaring reflector which forms a part of the headlight and is employed in di- 35 recting light-rays onto the face of the afore- said mirror.

Another object is to provide a headlight of the character indicated which is simple and durable in construction, readily install- 40 able on a motor-vehicle, and attractive in appearance.

With these objects in view, and to attain any other object hereinafter appearing, this invention consists in certain features of construction, and combinations and relative arrangements of parts, hereinafter described in this specification, pointed out in the claims, and illustrated in the accompanying drawings.

50 In said drawings, Figure 1 is a side view, in central section, of a headlight embodying my invention and shows the headlight supported from a forwardly projecting arm of the chassis-frame of a motor-vehicle.

55 Fig. 2 is a transverse section taken along

the line 2-2 in Fig. 1, looking forwardly. Fig. 3 is a section, in detail, taken along the line 3-3 in Fig. 2. Fig. 4 is a transverse section taken along the line 4-4 in Fig. 1, looking rearwardly. Fig. 5 is a horizontal 60 section taken along the line 5-5 in Fig. 1. Fig. 6 is a section taken along the line 6-6 in Fig. 4. Fig. 7 is a vertical section taken along the line 7-7 in Fig. 5. Fig. 8 is a section, in detail, taken along the line 8-8 65 in Fig. 1. Fig. 9 is a section, in detail, taken along the line 9-9 in Fig. 2. Figs. 8 and 9 are drawn on a larger scale than the other figures of drawings.

A support for my improved headlight 70 (see Figs. 1 and 5) is shown as comprising two laterally spaced standards or uprights 12 which at their lower ends are connected to and preferably integral with a substantially vertical post 13 adapted to be secured to a 75 convenient member of a motor-vehicle. Preferably the lower portion of said post has a downwardly facing shoulder 14 resting on a laterally projecting flange 15 of a forwardly projecting arm 16 of the chassis- 80 frame of said vehicle. Said post terminates at said shoulder in a downwardly projecting stud 17 which extends through and below the flange 15, and a nut 18 is threaded onto said stud and tightened against the under 85 side of said flange. The casing of my improved headlight comprises an external shell which is preferably formed of sheet- 90 metal and has two opposite spaced side walls 20 arranged between the standards 12. The upper end portion of each standard 12 (see Fig. 7) has an upwardly facing shoulder 21, and said standard terminates at said shoulder in an upwardly projecting stud 22 which extends through and above a rigid 95 member 23 which rests on said shoulder and is arranged externally of and preferably welded to the adjacent side wall 20, and a nut 24 is threaded onto said stud and tightened against the top of said member 23. 100 The side walls 20 extend (see Fig. 1) from a point rearward of the space between the standards 12 to a point a suitable distance forward of said space, and the shell comprising said walls also has an outwardly 105 curved forward end wall 25 arranged preferably wholly forward of and in the main above said space, and said forward end wall extends between and connects with the side walls 20. Said shell has an outwardly 110

- curved rearward end wall 26 extending between and connecting with the side walls 20 and arranged wholly rearward of the space between the standards 12, and said shell also
- 5 has a top portion 27 extending between and connecting with the end walls 25 and 26 and extending between and connecting with the side walls 20. The relative arrangement of the parts is such that the forward end wall
- 10 25 is considerably higher than the rearward end wall 26, and obviously therefore the lower end of the rearward end wall 26 is lower than the lower end of the forward end wall 25. Said shell (see Figs. 1, 2 and 4) is
- 15 braced and reinforced by two laterally spaced metal frames 28 arranged internally of the shell and constituting members of the headlight casing. Preferably each frame 28 has its central portion extending between
- 20 the upper ends of the end walls 25 and 26 and bracing the top portion 27 of said shell and has its opposite end portions extending substantially to the lower ends of and contoured as required to conform to and bracing opposite end walls 25 and 26 respectively, and said shell is preferably welded to and therefore rigid with said frames. By the construction hereinbefore described it will be observed (see Figs. 1, 2 and 4) that said
- 25 shell has an opening 29 formed at the bottom and lower portion of the front of the casing and extending between the lower ends of the side walls 20 and between the lower ends of the end walls 25 and 26.
- 30 Said shell or casing is provided with an inclined light-transmitting slide-forming panel 30 shown closing the opening 29. Said panel is composed preferably of plate glass and extends straight between the lower ends
- 35 of the end walls 25 and 26. The outer side of said panel therefore faces forwardly and downwardly, and said panel is supported from the casing. Each side wall 20 is shown extending, as at 31, (see Figs. 2 and 4) to
- 40 and overlapping the inner side of the adjacent side marginal portion of the panel 30. Each of the end walls 25 and 26 is shown extending, as at 32, (see Fig. 1) to and overlapping the inner side of the adjacent end
- 45 marginal portion of the panel 30. The hereinbefore mentioned shell is provided with a metal frame 33 which overlaps the outer side of the forward and rearward marginal portions of the light-transmitting panel 30,
- 50 as shown in Fig. 1, and extends opposite the forward and rearward edges of said panel and adjacent said edges is welded to and therefore rigid with said shell.
- 55 Internally of the forward end portion of the headlight casing and over the forward and upper end portion of the light-transmitting panel 30 (see Figs. 1 and 2) is arranged a rearwardly facing flaring reflector 38 which is arranged substantially at a
- 60 right angle to said panel and surrounds an incandescent electric lamp 39 arranged centrally of and mounted in the reflector and supplied with electric current in any approved manner. Said reflector is provided at its diametrically larger end and externally with an annular flange 40 (see also Fig. 9) removably secured by screws 41 to a quadrangular frame 42 which surrounds the reflector and is interposed between said flange and lugs 43 formed on the reinforcing frames 28. The frame 42 is removably secured to the lugs 43, and therefore to the frames 28, by screws 45.
- 65 Internally of the rearward end portion of the headlight casing (see Figs. 1, 4 and 6) is an upright mirror arranged transversely in relation to the casing and having its face formed by a glass plate coated at its rear side in any approved manner to form a light-reflecting panel 47. Said light-reflecting panel is mounted in a metal frame 48 which extends circumferentially of said panel, and a metal plate 49 is arranged to form a covering for the rear sides of said panel and frame, and (see Figs. 4 and 8) is removably secured to said frame by screws 50. The frame or portion 48 of the mirror is hinged or pivoted at its lower end, as at 51, to the lower ends of the rear end portions of the frames 28, as shown in Figs. 1 and 4, and has a substantially horizontal axis. Said mirror is arranged and free to be swung forwardly. The relative arrangement of the parts is such that the mirror is arranged lower than and faces the flaring reflector 38 and also faces the light-transmitting panel 30, that said panel extends upwardly and forwardly to a point under and near said flaring reflector from a point under and near the mirror, that said panel participates in the formation of the bottom as well as in the formation of the lower portion of the front of the headlight, that said flaring reflector directs light, upon lighting the lamp 39, onto the face of the mirror, and that rays of light received by said face from said flaring reflector and from the lamp are projected from the mirror to and through the panel 30 and over and onto the roadway in front of the vehicle.
- 70 100 105 110 115 120 125 130
- Each frame 28 (see Figs. 1, 4 and 8) is provided adjacent and forward of the upper portion of the frame or portion 48 of the mirror with a downwardly projecting rigid arm 53 which extends opposite the forward side of said portion of and is spaced from the mirror, and the lower end portion of said arm is provided in front of said portion of the mirror with a slot 54 extending endwise of the arm and from the forward side to the rear side of the arm and engaged by a pin 55 which is rigid with and arranged substantially at a right angle to the mirror and projects forwardly from the mirror-frame to and through said slot and

a suitable distance forwardly of said arm. Said slot is arranged to accommodate the location of said pin during any desired forward or rearward movement or adjustment 5 of the mirror, and onto said pin is threaded a nut 56 which abuts at the sides of said slot against the forward side of said arm, and said nut and said arm cooperate in forming a stop for limiting rearward movement of the mirror. On each pin 55 is mounted a coiled spring 57 confined on the pin between the mirror and the adjacent arm 53. The springs 57 on the pins 55 are under tension in the rearward and normal position of the mirror and therefore act to swing the mirror rearwardly, but said springs are only partially compressed in said position of the mirror so as to permit swinging of the mirror forwardly against 10 the action of the springs. It will also be observed that the mirror is readjusted in relation to the arms 53 of the frames 28 by a readjustment of the nuts 56 endwise of the pins 55.

25 As hereinbefore indicated, the springs 57 act to retain the mirror in its rearward and normal position, and I would here remark that improved means (see Figs. 1, 4 and 6) for actuating the mirror forwardly to cause 30 the light-rays received by the mirror from the reflector 38 and lamp 39 to be projected from the mirror through the light-transmitting panel 30 and onto the roadway in closer proximity to the front of the vehicle, 35 comprise a substantially horizontal shaft 58 spaced rearwardly from the mirror and arranged internally of the rearward end portion of the casing and lower than the top edge and higher than the axis of the mirror.

40 Preferably said shaft is substantially parallel with the axis of the mirror and supported from forwardly projecting arms 59 with which the rearward end portions of the frames 28 are provided. Said shaft has two 45 upwardly and forwardly projecting arms 60 spaced endwise of the shaft and arranged adjacent opposite side edges respectively of the mirror and engaging the back-plate 49 of the mirror in the rearward and normal 50 position of the mirror. Said shaft is provided, centrally between its ends, with a downwardly projecting arm 61 to the lower end of which is attached a cable 62 which extends rearwardly through an aperture 63 55 in the rear end wall 26 of the casing to within convenient reach or control of the driver of the vehicle equipped with the headlight. Obviously a pull upon said cable rearwardly results in the rotation of the shaft 58 in the direction required to effect 60 forward movement of the mirror against the action of the springs 57.

What I claim is—

1. A headlight comprising a shell having 65 a rearward wall and a forward wall the

lower end of which is higher than the lower end of the first-mentioned wall and also having a top portion extending between said walls and an opening extending between said ends of said walls, two laterally spaced frames internally of said shell and bracing said walls and the aforesaid top portion of said shell, an inclined light-transmitting panel arranged to form a closure for the aforesaid opening, a rearwardly facing flaring reflector internally of the forward portion of the aforesaid shell, means for illuminating said reflector, and a mirror internally of the rearward portion of said shell and facing the flaring reflector and the aforesaid panel, said flaring reflector and the mirror being supported from the forward portion and rearward portion respectively of each of the aforesaid frames. 70

2. A headlight comprising a shell which has forward and rearward walls and a top portion extending between said walls and has the lower end of its forward wall higher than the lower end of its rearward wall and also has an opening extending between said ends of said walls, two laterally spaced reinforcing frames internally of said shell and arranged to brace said walls, an inclined light-transmitting panel arranged to form a closure for the aforesaid opening, a rearwardly facing flaring reflector internally of the forward portion of the aforesaid shell, means for illuminating said reflector, a mirror internally of the rearward portion of said shell, and a frame extending between the upper and lower ends of the forward end portions of and secured to the aforesaid reinforcing frames and arranged transversely of said shell and supporting the aforesaid flaring reflector. 80

3. A headlight comprising a shell which has forward and rearward end walls and a top portion extending between said walls and has the lower end of its forward end wall higher than the lower end of its rearward end wall and also has an opening extending between said ends of said walls, two laterally spaced reinforcing frames internally of said shell and arranged to brace said walls, an inclined light-transmitting panel arranged to form a closure for the aforesaid opening, a rearwardly facing flaring reflector internally of the forward portion of the aforesaid shell, a lamp internally of said reflector, a mirror internally of the rearward end portion of said shell, and a frame extending between the upper and lower ends of the forward end portions of and secured to the aforesaid reinforcing frames and arranged transversely of said shell, the flaring reflector being provided at its diametrically larger end and externally with a circumferentially extending flange overlapping and secured to said frame. 100

4. A headlight comprising a casing hav- 110

ing a forward wall and a rearward wall the lower end of which is lower than the lower end of the first-mentioned wall and also having an opening extending between said ends of said walls, an inclined light-transmitting panel arranged to form a closure for said opening, a rearwardly facing flaring reflector internally of the forward portion of the casing, means for illuminating said reflector, a mirror internally of the rearward portion of the casing and spaced forwardly from the aforesaid rearward wall and pivoted at its lower end and facing the flaring reflector and the aforesaid panel and arranged and free to be swung forwardly, means arranged adjacent the upper end of the mirror and acting to swing the mirror rearwardly, means for limiting rearward movement of the mirror, a shaft substantially parallel with the axis of the mirror and arranged between the mirror and the aforesaid rearward wall and having two upwardly projecting arms which are spaced endwise of the shaft and arranged to actuate the mirror forwardly during rotation of the shaft in the required direction, and means for effecting said rotation of the shaft.

5. A headlight comprising a casing having a forward wall and a rearward wall the lower end of which is lower than the lower end of the first-mentioned wall and also having an opening extending between said ends of said walls, an inclined light-transmitting panel arranged to form a closure for said opening, a rearwardly facing flaring reflector internally of the forward portion of the casing, means for illuminating said reflector, a mirror internally of the rearward portion of the casing and pivoted at its lower end and adapted to be swung forwardly and facing the flaring reflector and the aforesaid panel and provided with two forwardly projecting pins arranged adjacent opposite side edges respectively of the mirror, members rigid with the casing and spaced forwardly from the mirror and having slots which are engaged by said pins and arranged to accommodate the location of the pins during forward movement of the mirror, springs mounted and confined on said pins between the mirror and the slotted members, said pins extending through said slots and forwardly of the slotted members, and nuts threaded onto said pins at and overlapping the forward sides of said slotted members.

40

45

50

threaded onto said pins at and overlapping 55 the forward sides of said slotted members.

6. A headlight comprising a casing having a forward wall and a rearward wall which is lower than the first-mentioned wall and also having an opening extending between 60 the lower ends of said walls, an inclined light-transmitting panel arranged to form a closure for said opening, a rearwardly facing flaring reflector internally of the forward portion of the casing, means 65 for illuminating said reflector, a mirror internally of the rearward portion of the casing and pivoted at its lower end and adapted to be swung forwardly and facing the flaring reflector and the aforesaid panel 70 and provided with two forwardly projecting pins arranged adjacent opposite side edges respectively of the mirror, members rigid with the casing and spaced forwardly from the mirror and having slots which are engaged by said pins and arranged to accommodate the location of the pins during forward movement of the mirror, springs mounted and confined on said pins between the mirror and the slotted members, said 75 pins extending through said slots and forwardly of the slotted members, and nuts threaded onto said pins at and overlapping the forward sides of said slotted members.

7. A headlight comprising a shell having 80 a forward wall and a rearward wall which is lower than the first-mentioned wall and also having an opening extending between the lower ends of said walls, two laterally spaced frames internally of said shell, an 85 inclined light-transmitting panel arranged to form a closure for said opening, a rearwardly facing flaring reflector internally of the forward portion of the aforesaid shell and supported from the aforesaid frames, a 90 lamp internally of said reflector, a mirror internally of the rearward portion of said shell and pivotally connected at its lower end to said frames and facing the flaring reflector and the aforesaid panel and 95 adapted to be swung forwardly, means acting to swing the mirror forwardly, and means for limiting rearward movement of the mirror.

In testimony whereof I sign the foregoing 105 specification this 1st day of October, 1921.

PERCY W. WHITE.
